UNITED STATES PATENT OFFICE

PETER J. WERNER AND JOHN SOBCZAK, OF MILWAUKEE, WISCONSIN

MINIATURE DOMICILE TREE HOLDER

Application filed February 6, 1929. Serial No. 338,008.

This invention relates to Christmas-tree holders of that variety where novelty, in the way of miniature replicas of well-known objects, combine with the utilitarian purpose of the holders aforesaid.

The objects of the invention are: the providing of a safe and ornamental tree holder that will allow for innovations which will keep up the interest in festive customs. The 10 providing of a braced tree holder which has all its mechanical-structural aspects masked in forms that present a more pleasing aid to the imagination. The providing of illuminated means for an otherwise darkened and hidden area, which invites the attention of observers by the pleasing effect produced. And the offering of an object which will provide an economical device that will dually function as an element of 20 juvenile interest aside from its uses as a tree support.

The figures of the drawing are indexed as follows:—

Fig. 1 is a rear elevation of the invention, 25 its use being indicated by the tree shown in dotted line.

Fig. 2 is a side elevation, broken away to disclose the interior.

Fig. 3 is a sectional plan view taken on 30 line 3—3 of Fig. 2.

Fig. 4 is a diagrammatic view of the tree-centering means.

Similar characters of reference apply to like parts throughout the several views.

35 Referring more particularly to the drawings, D is a miniature reproduction of a bungalow, or domicile, having all the essential elements that usually appear in replicas common to the doll's-house class. The house 40 rests upon an integral base or yard B, which extends beyond the outline of the house proper, so that a wide area is covered for insuring against any tilting tendency, and, also, for allowing the placing of other objects that may be added as seasonal adjuncts. 45 The walls will have transparencies in the form of windows, some of which may be free to open upon occasion.

The roof is in two parts; one half is R, 50 hinged to the rear wall at H; the other half,

R' is an integrally fixed part of the general structure D. The chimney C is complete as to its outward portion; this element is integrally part of the roof section R, the bottom being scribed to rest upon the section 55 R' when the closed position is assumed. Both roof sections R and R' are cut out to offer an opening that registers with the chimney's interior. Thumb screws S are tapped through the four walls of the chimney C as 60 shown, and these elements will lock in position any diameter of tree trunk that will approximate the opening occurring in said chimney. The roof portions, R—R', when 65 closed, due to their being attached to the vertically rigid walls, are virtually compression members that resists all thrusts which may arise from any sway action happening through accident, and offers a safe mechanical method of transferring such forces down 70 to the broad expanded base B. The door-like part of the roof, R, gives access to the interior of the domicile D for introducing the tree-illuminating wire W', which is 75 passed through the chimney C before the tree trunk T is inserted; the wire W', having the customary plug-in element P, can be passed to the outside again through the opening Na to where it will connect with the tap unit M. The said unit provides for a plurality 80 of connections that will serve for a variety of uses in the distribution of electric current. The hinging of the door portion R will allow also, of free access to the house interior when the device is functioning as a 85 doll's-house.

Directly under the chimney C, in the floor F of the house D, is fashioned a basin-like depression W for holding water that is absorbed by the tree; there is a further depression of cone-like form, centrally aligned with the chimney's aperture which functions as a self centering means for the tree trunk T. This latter depression is a point of rest that combines with the clamping screws S, and the bracing effect of the roof portions R and R' to form the mechanically structural combination which will maintain the tree in a fixed vertical position.

The basin W may, upon occasion, be cov- 100

ered by a suitable plate V, leaving the floor F smooth for such purposes as dolls' houses are used.

The base B is grooved at G for wires W² which convey the electric current for lamps L that illuminate the house interior, leaving the said base clear of obstructions for resting upon flat surfaces.

A house-current wire W will service the invention from any convenient outlet or socket, and the domicile itself will be tinted to represent those effects common to structures of this classification.

Having described the invention, what is claimed as being patentably novel and deserving of protecting by Letters Patent, is:—

An article of manufacture having, an inclosure accessibly covered, a hinged cover portion integrally combined with a rectangular tube, a fixed centering rest within said inclosure, and means residing in said tube for limiting the hinged portion to complete the inclosure cover when locating the rectangular tube spacedly above and axially aligned with the aforesaid centering rest.

In testimony of which we hereunto affix our signatures.

PETER J. WERNER.
JOHN SOBCZAK.
